UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

MEANS FOR CONTROLLING THE TEMPERATURE OF PLATE-CASTING BOXES.

1,197,893.

Specification of Letters Patent. Patented Sept. 12, 1916.

Application filed April 17, 1915, Serial No. 22,153. Renewed February 16, 1916. Serial No. 78,780.

To all whom it may concern:

Be it known that I, HENRY F. BECHMAN, a citizen of the United States, residing at Battle Creek, in the county of Calhoun and 5 State of Michigan, have invented certain new and useful Improvements in Means for Controlling the Temperature of Plate-Casting Boxes; and I hereby declare that the following is a full, clear, and exact description thereof, reference being had to the accompanying drawings, which form part of 10 this specification.

This invention relates to stereotype plate casting boxes, and its object is to provide 15 means for maintaining the parts of the casting box at a temperature most suitable for plate casting while preventing overheating thereof, by maintaining a body of water, or other suitable medium, at a temperature approximating the boiling point within the 20 hollow portions of the casting box subjected to most direct contact with the molten stereotype metal, so that such parts will be protected from injury and maintained at such 25 a substantially uniform temperature as will enable plates to be cast in such boxes more uniformly and with greater rapidity than has been heretofore practical with casting boxes of the same general type but to which 30 this invention has not been applied.

The invention is particularly designed for use in connection with stereotype casting boxes of the type shown in my Patent No. 945,678, of January 4, 1910, but is applicable 35 to other forms of plate casting boxes and I will explain the invention as applied to such a casting box particularly designed for casting "tubular" plates.

In the accompanying drawings forming 40 part of the specification: Figure 1 is a sectional elevation of part of such a casting box showing the temperature regulating means. Fig. 2 is a detail sectional view showing the box core in position for removing a cast plate. Fig. 3 is a detail transverse section of such a box on line 3-3, Fig. 1.

The box shown in the drawings is a so-called "tubular plate" casting box of the type shown in my aforesaid patent, and comprises a base 7 to which are secured side

frames 9 upon which is mounted a drag 1 provided with a semi-cylindric recess in its front face to accommodate the tiltable core 2, when the latter is in casting position.

To the drag 1 is hinged a cope 1^a which 55 can be swung to and from the drag, and has a semi-cylindric recess in its inner face so that when the box is closed, as indicated in Fig. 3, the opposed recesses in the drag and cope form a truly cylindric chamber within 60 which is the core 2.

The core 2 is mounted on trunnions 3 journaled in the side frames 9, so that said core can be swung or tilted to a position axially of the said chamber, (Figs. 1 and 3) when 65 a plate is to be cast; or when the box is opened can be tilted outwardly to a substantially horizontal position, as indicated in Fig. 2, to facilitate the removal of the cast plate. The said core has been heretofore made hollow and provided with interior pipes suitably connected with exterior water supply and exhaust pipes by which water can be circulated through the box during the casting operations. 70

The parts thus far described are substantially the same as those shown in my aforesaid patent and are not specifically claimed herein. 75

It is desirable both to prevent overheating of the core, or part with which the molten stereotype metal directly contacts, during the casting operations and at the same time prevents such sudden or excessive changes in temperature of such parts as 80 would affect the uniformity of plates cast therein. The water circulating systems heretofore employed have not given the desired results. In applying my invention to such a box the said core is provided with but 85 one internal pipe 11 which communicates at bottom with a passage 3^a leading through one of the trunnions 3 and connected to an elbow 4 at the outer end of such trunnion, and the elbow 4 is connected by a flexible 90 pipe or hose section 4^a to a pipe 5 leading into a reservoir or tank 6 mounted on any suitable support, as 8, at any desired elevation. The pipe 5 preferably extends into the tank to a point above the normal water 95 100

2

level therein, which is indicated at *w* in Fig. 1, and the part of said pipe within the tank is preferably numerously perforated, as indicated in the drawing. A water gage 6^a attached to the tank enables the proper level of water therein to be determined. The medium in the tank may be heated to a temperature of approximately 200° F. by external means not shown, but will ordinarily be heated by contact with the core which is heated by the molten metal during the casting operations. When I herein refer to such medium as "water" I do not intend to restrict the invention to the use of water.

15 When the box is ready for casting a plate, the core 2 is in a vertical position, (Fig. 1) and the core and all the connections between it and the tank, below the water line *w*, are filled with water. If the water in the core or box becomes overheated during plate casting operations the expansion would tend to force the water back through pipes 11 and 5 into the tank but if any such action occurs immediately the pipes and core will be filled with cooler water from the tank 6.

20 It will be seen that with this invention the core or hollow part of the box when in operative position is filled with hot water which prevents its overheating and at the same time prevents its sudden chilling, because the water is kept at approximately boiling point during the casting operations.

25 A small amount of steam may collect at the top of the core during each casting operation, but if this steam pressure becomes excessive, it could easily escape back into the tank through pipes 11, 4, 4^a and 5 and be dissipated through the perforations in the pipe. In the box shown, when the core is lowered to remove the plate, as indicated in Fig. 2, this produces a mechanical agitation of the hot water in the core; and water in the core is disturbed and shifted, and the upper end of the core is lowered to approximately almost the level of the trunnion 3 at which time any boiling water could readily escape through the pipes 11, 4 and 5 to the tank being replaced by cooler water. The temperature of the water in the tank will be maintained at about boiling point by the heat of the molten metal around the core at each plate casting operation; and on the other hand the temperature of the core will be maintained at an approximately uniform temperature by the body of hot water constantly maintained therein at approximately boiling point. The lowering and raising of the core causes an ebb and flow of hot water in the core each time the core is lowered to remove a plate; and I have found this sufficient in practice to maintain the core at a safe practically uniform casting temperature without requiring a con-

stant circulation of the fluid medium through the box.

65 It will be seen that if steam collects in the core it could only force water out of pipe 11—while a large body of water remains in the core around such pipe—but if the steam forces the water back in pipe 11 when the box is closed, its escape is facilitated when the core is lowered, and water will enter the core immediately to fill the space occupied by the escaped steam.

70 It will be observed that there is but one conduit or passage for the medium between the tank and the core, through which passage both any excessive pressure in the core will be relieved, and the supply of medium in the core be maintained.

80

75 A casting apparatus equipped with this invention can be maintained at practically any desired uniform temperature according to fluid medium used. The most practical temperature is about 200° F. which prevents overheating and is very desirable as at such temperatures the plates will not stick to the box; whereas if the box is chilled suddenly or heated irregularly the plates are chilled unequally while being cast, and therefore 85 have to be machined before they can be used. If the core was not protected from overheating it might become so hot that the stereotype metal would adhere thereto, causing great annoyance and delay, but with 90 boxes equipped with my invention overheating is prevented and plates can be cast as fast as the operators can manipulate the box.

95 What I claim is:

100 1. In a stereotype casting apparatus, the combination of a box having a hollow member, with an interior fluid conduit, a tank exterior to the box, and a single fluid conduit connecting said tank with the conduit in the said member.

105

105 2. In a stereotype casting apparatus, the combination of a box having a hollow tiltable member, a conduit within said member, a tank exterior to the box, and a single pipe connection between said tank and the conduit in the said member.

110

115 3. In a stereotype casting apparatus, the combination with a box having a hollow tiltable member, a pipe within said member, a tank exterior to the box, and a single pipe connection between said tank and the pipe in said tiltable member.

120 4. In a stereotype casting apparatus, the combination of a casting box having a hollow member, a pipe within and extending nearly to the upper end of said member, a tank exterior to the box, and a single fluid conduit connecting the said tank with the lower end of the pipe in the said member.

125 5. In a stereotype casting apparatus, the combination of a casting box having a hol-

low tilttable core, a pipe within said core and
extending nearly to the upper end thereof
and open at its upper end, a tank exterior
to the box, and a single pipe connection be-
tween the said tank and the lower end of
the pipe in said core.

In testimony that I claim the foregoing as

my own, I affix my signature in presence of
two witnesses.

HENRY F. BECHMAN.
